UNITED STATES PATENT OFFICE

2,619,031

MARKING OUT FABRIC

Aage Rothenborg, Copenhagen, Denmark

Application September 20, 1946, Serial No. 698,271

12 Claims. (Cl. 101—26)

1

This invention relates to a method and drill for marking fabric, and more particularly for marking a pile of many layers of cloth by drilling small holes through the cloth and simultaneously applying color at the edges of the drill holes, and the object of the invention is to provide a method in which the drilling and simultaneously the application of color can be obtained rapidly and with security.

A further object of the invention is to provide a device for drilling holes and simultaneously applying color which is simple in construction and reliable in operation.

Still a further object of the invention is to provide an improved marking drill adapted to use powder or chalk, in which a uniform supply of powder or chalk can be fed to a pile of cloth. A special object in this connection is to provide a marking drill in which the powder is fed forward without damage or clogging in the feed channel.

Further objects and advantages according to the invention will appear from the following specification and the appended claims.

Reference will now be had to the accompanying drawing, in which

Figure 1 is a sectional elevation of a machine in accordance with the invention,

Figure 2 is a vertical section taken on line 2—2 in Fig. 1,

Figure 3 is a side elevation of one end of the machine showing a special starting device,

Figure 4 is a sectional view showing another form of the starting device, and

Figure 5 is an elevation showing on an enlarged scale the tip of the needle and a small portion of the receptacle for the pigment.

In the drawing, 1 is a base plate forming a support for the textiles to be marked out. A bracket 2 is secured to the base plate near one end thereof and extends over the base plate from one end thereof adjacent to and above the opposed end thereof. A vertical hollow shaft 3 is mounted in ball-bearings 4 and 5 at the free end of the bracket 2 and has a belt pulley 7 secured thereto as by means of a set-screw 6, Fig. 2. An electric motor 8 having a belt pulley 9 is mounted on the base plate 1 within the foot of the bracket 2, and is connected with the belt pulley 7 by means of a driving belt 10 which, in the form shown, runs over guiding or idler pulleys 11.

A spindle 12 is slideable axially, in the hollow shaft 3, and is held against rotation relatively to the shaft 3 by a keyway 13 which is engaged by a key disposed within the shaft 3 so as to

5 prevent relative rotation of the spindle and the shaft but permitting a relative sliding movement thereof. The spindle 12 carries near its lower end a ball-bearing 15, the outer ring of which is slidably guided in a tube 16 extending in a vertical downward direction from the arm 2. Two laterally extending pins 17 are secured to the outer ring of the ball-bearing 15. The pins 17 engage vertical slots 18 in the tube 16 and are connected with a yoke-shaped portion 19 of a hand-lever 20 mounted for vertical pivoting movement on the bracket 2. To permit the lever portion 19 to follow the linear movement of the pins 17 which, as stated above, are guided in the slots 18, the pivot 21 of the lever 20 is mounted for substantially horizontal sliding movement in slots 22 in the bracket 2. A needle 23 is screwed into the lower end of the spindle 12 in axial alignment therewith, thus mounted for vertical sliding movement relatively to the base plate 1.

10 Another tube 24 telescoping on the tube 16 is provided with vertical slots 25 through which the pins 17 extend and by means of which said tube 24 is supported upon said pins in inoperative position shown in the drawing. The tube 24 is at its lower end provided with an end plate 26, and between this end plate and the outer ring of the ball-bearing 15 a helical compression spring 27 is inserted. The end plate 26 is provided with an aperture 27a through which the needle 23 extends. A casing 28 is by means of a screw-threaded socket 29 screwed to the lower end of the tube 24 in axial alignment therewith. The casing is provided with a top plate 30 having an aperture through which the needle 23 extends. Another aperture for the needle is provided at the bottom of the casing. This aperture forms a sliding or running fit with the needle 23 so that the latter will close the aperture. As shown in the drawing, the length of the needle 23 is such that the lower end of the needle will just close the bottom aperture of the receptacle 28 in the inoperative position shown in the drawing.

15 The casing 28 encloses a chamber adapted to receive a pulverulent pigment, which preferably consists of a dry powder or chalk and which is intended to be introduced into the textiles to be marked out by means of the needle 23.

In use a plurality of layers of textiles to be marked out are supported on the base plate 1, if desired together with a templet, according to which the marking out is to be effected. After 20 the motor 8 has been started, the hand-lever 19,

20 is manually depressed, whereby the needle 23 as well as the tube 24 with the casing 28 secured thereto are lowered towards the textiles while the needle rotates.

When the bottom of the casing 28 engages the upper textile layer, the casing and the tube 24 are stopped. The spindle 12 with the needle 23 are however urged further downwards by means of the hand-lever 19, 20 and against the action of the spring 27 so that the needle 23 penetrates the several layers of textiles. As shown in Fig. 5, the needle is provided with a helical surface groove through which the pigment contained in the receptacle 28 can flow along the needle and dispose itself on the textile around the holes made by means of the needle.

The direction of the helical groove 31 is chosen in such a manner relative to the direction of rotation of the shaft 3 and the needle 23 that the groove tends to expel the pigment from the receptacle 28 through the bottom aperture thereof somewhat in the manner of a screw conveyor. As indicated by an arrow 32 in Fig. 5, it is assumed that the shaft 3 rotates in a clockwise direction as seen from above. In accordance herewith the groove 31 extends in a counter-clockwise direction as shown in Fig. 5. Hereby sufficient pigment is fed from the chamber through the groove of the needle to all of the layers of textile supported on the base plate 1.

In order to prevent the tip of the needle 23 from being damaged through contact with the base plate 1, the latter is provided with an aperture 33 situated in axial alignment with the needle 23. A small receptacle 34 is provided immediately below the aperture 33 for receiving excessive pigment, if any. Downward movement of the needle 23 is limited by the pin 17 abutting against the lower end of the slots 18 of the tube 16 so as to ensure penetration of the lowermost layer of textile by the needle but preventing the needle from making contact with the bottom of the receptacle 34.

When used for marking out large pieces of textile, the machine may conveniently be portable so that it can be moved along the textile as the marking out proceeds. To this end, the base plate 1 is preferably relatively thin and bevelled at its edges as shown in Figs. 1 and 2 so that it can easily be introduced under a pile of textiles disposed upon a table. In order to facilitate introduction of the base plate under the textiles the base plate is provided with small rollers 35.

In Fig. 3, a small push-button switch 36 is secured to the casing 28 and has its push-button 37 extending vertically a small distance below the level of the bottom of the casing 28. The switch 36 is connected with the motor 8 by means of a cable 38. When the casing 28 and the needle 23 are lowered towards the upper side of a pile of textiles by means of the lever 19, 20, the push-button 37 will engage the upper side of the pile so as to be actuated during further downward movement of the casing 28. The switch 36 will thereby close the circuit of the motor 8 so as to start the same. When the push-button is again disengaged from the textiles the motor stops.

In the form shown in Fig. 4, a push-button switch 39 is secured to the lever 19, 20, and its push-button 40 is adapted to co-operate with one arm of a two-armed lever 41 mounted in the yoke 19 and carrying a roller 42 on its other arm. The lever 41 is carried by a torsional spring 43 which tends to urge the lever 41 to press the push-button 40 but is prevented therefrom by the roller 42.

engaging the shoulder on the tube 16. When the lever 19, 20 is manually depressed against the action of a spring (not shown) the roller 42 will be disengaged from the shoulder of the tube 16 so as to permit the torsional spring 43 to actuate the push-button 40 so as to close the circuit of the driving motor of the machine.

The invention is not limited to the specific embodiments described and shown in the drawing, which may be varied and modified in several respects within the scope of the appended claims.

I claim:

1. A marking drill device of the character described comprising a base plate, a bracket extending over said base plate, a displaceable tube at the end of said bracket, a color chamber carried by the lower end of said tube, an opening in the bottom of said color chamber, a needle having a helical groove along its surface slidably arranged within said tube so as to extend through said bottom opening, means for rotating said needle in a direction opposite to the winding direction of said helical groove, and means including a handle for longitudinal displacement of said tube to cause said color chamber to engage the upper layer of a pile of cloth arranged upon said base plate and for further displacing said needle through the opening in said color chamber through the layers of cloth after engagement of said color chamber with said upper layer.

2. A marking drill device of the character described comprising a base plate, a bracket extending over said base plate, a displaceable tube at the end of said bracket, a color chamber carried by the lower end of said tube, a needle having a helical groove along its surface arranged within said tube and extending through an opening in the bottom of said color chamber, a spring connection between said needle and said tube for normally holding said tube and color chamber extended, means for rotating said needle in opposite direction to the winding direction of said helical groove, and a handle for moving said tube to cause said color chamber to engage the upper layer of a pile of cloth arranged upon said base plate, and for thereafter displacing said needle through the opening in said color chamber and through the layers of cloth against the resistance offered by said spring connection.

3. The process of marking out fabric comprising rotating a substantially cylindrical needle having a helical groove along its surface in the opposite direction of the winding of the groove seen from the top, forcing the needle into said cloth during the rotation of the same for penetrating super-imposed layers of fabric, and feeding powder to said groove at a point substantially at the top layer of the layers of fabric.

4. A method of marking cloth arranged in a plurality of superimposed layers, by means of a rotary needle having a helical groove on the outer surface thereof, which comprises feeding color to said groove, forcing said needle into said cloth, and rotating said needle in a direction to cause said grooved needle to act as a screw conveyor to convey color to said layers.

5. In powder marking apparatus, a substantially cylindrical drill having a helical groove along its surface, means for rotating said drill in a direction opposite to the direction of the winding of said groove as seen from the top, and means for feeding colored powder to said groove.

6. The method of marking out fabric comprising rotating a needle having a helical groove in opposite direction of the winding of said groove

seen from the top, with part of said grooved needle in a powder supply and another part of said grooved needle penetrating a stack of layers of fabric thereby screwing out said powder from said supply through said layers.

7. In a marking drill, a substantially cylindrical needle having a helical groove along its cylindric surface, means for rotating said needle in a direction opposite to the winding direction of said helical groove, means for feeding colored powder to said helical groove, and means for displacing said needle in longitudinal direction.

8. In fabric marking apparatus, a support, a casing enclosing a chamber mounted for movement relatively to said support, a needle mounted to move through said chamber and having a helical groove, means for moving said chamber relatively to said support toward and from the fabric to be marked, means for moving said needle relatively to said chamber and to said support, and means for rotating said needle in the opposite direction of the winding of said helical groove as seen from the top.

9. In fabric marking apparatus, a support for the fabric to be marked, a casing enclosing a chamber mounted for vertical sliding movement relatively to said support, manually operated means for moving said casing, an aperture in the bottom of said casing, a spring elevated needle positioned for vertical movement through said chamber and extending into said aperture in said casing, said needle being formed with a helical groove, means responsive to a resistance against the movement of said chamber to transmit the movement to said needle through said aperture, and means for rotating said needle opposite the winding direction of said helical groove, as seen from the top, whereby said groove conveys color from said chamber to the several layers of said fabric.

10. In fabric marking apparatus, a support for the fabric to be marked, a casing enclosing a chamber mounted for vertical sliding movement relatively to said support, manually operated means for moving said casing, an aperture in the bottom of said casing, a spring elevated needle positioned for vertical movement through said chamber and extending into said aperture in said casing, said needle being formed with a helical groove, means responsive to a resistance against the movement of said chamber to transmit the movement to said needle through said aperture, means for rotating said needle opposite the winding direction of said helical groove, as seen from the top, whereby said groove conveys color from said chamber to the several layers of said fabric, and means responsive to said resistance against

the movement of said chamber to energize the means to rotate said needle.

11. In fabric marking apparatus, a support for the fabric to be marked, a casing enclosing a chamber mounted for vertical sliding movement relatively to said support, manually operated means for moving said casing, an aperture in the bottom of said casing, a spring elevated needle positioned for vertical movement through said chamber and extending into said aperture in said casing, said needle being formed with a helical groove, means responsive to a resistance against the movement of said chamber to transmit the movement to said needle through said aperture, an electrical motor for rotating said needle opposite the winding direction of said helical groove, as seen from the top, whereby said groove conveys color from said chamber to the several layers of said fabric, and switch means responsive to the movement of said manually operated means to energize said motor.

12. In a fabric marking apparatus, a chamber for a mass of colored powder and having an opening, a needle mounted to move through said chamber and having a helical groove, means for rotating said needle in the opposite direction of the winding of said helical groove as seen from the top, and means for moving said needle in axial direction to a position extending through said opening of said chamber to convey colored powder forwardly therefrom along said helical groove.
